UNITED STATES PATENT OFFICE.

CHARLES WHITFIELD, OF SYDENHAM, LONDON, ENGLAND.

GAS-PRODUCER.

1,096,774.

Specification of Letters Patent. Patented May 12, 1914.

Application filed February 3, 1914. Serial No. 816,163.

To all whom it may concern:

Be it known that I, CHARLES WHITFIELD, a subject of the King of Great Britain and Ireland, and resident of Sydenham, London, 5 England, have invented certain new and useful Improvements in Gas-Producers, of which the following is a specification.

This invention refers to gas producers for use in the making of producer gas and 10 it relates in particular to producers of the type designed to deal with light fuels, *i. e.* fuels, the non-gaseous and dust-like products of which are liable to pass with the gas and choke the passages leading to the point 15 where the gas is required. This is especially so in the case of light fuels of a bituminous or tarry nature, and where the producer is worked by the suction stroke of an engine. Attempts to overcome this objection have 20 been made, chiefly consisting in washing out the dust after the gas leaves the producer. By this invention the dust is removed before the gas leaves the producer, or, in other words, the dust is left in the producer.

A further feature of the invention is the treatment of the gas in a special construction of centrifugal fan which while removing any dust or tar (if any) remaining in 30 the gas produces a steady and gentle suction on the producer and modifies the irregular and intermittent engine suction.

Upon the accompanying drawings, Figure 1 illustrates a sectional elevation of a 35 gas producer plant embodying the invention. Fig. 2 illustrates a sectional plan of the producer part only. Fig. 3 illustrates an enlarged vertical section of an important detail part. Fig. 4 illustrates a sectional plan on line $x-x$ of Fig. 3. Fig. 5 illustrates a sectional elevation of the tar extractor.

As shown, the producer is of ordinary 45 construction generally, but the gas outlet a , which is preferably straight-sided, is much wider in plan at the end nearest the interior of the producer than at the end farthest from such interior. To the metal part a 50 of the gas outlet is connected the junction box b provided with cleaning and inspection doors, and from this box depends a short pipe c . Connected to this pipe at its lower end, by a tapered connected pipe d , is a pipe e , this pipe being larger in diameter 55 than the pipe c . Supported by a flange or

ledge in the lower end of the pipe e , see Fig. 3, is a conical nozzle f , the lower part of this nozzle extending into the tapered connecting pipe d . Fitted tangentially to the pipe e , near its upper end, is a water 60 supply pipe g . By means of this pipe water delivered therefrom, flows in a spiral path around the inner face of the pipe e , thereby keeping the same constantly washed and free from tar and dust. The lower and 65 open end of the pipe e dips into a settling tank h . Near its lower end the pipe e is connected by branch pipe h' to a further pipe i , which at its lower and open end dips into the tank h . At its upper end the pipe i 70 communicates with pipe j , which latter and also through the tank t and extractor o communicates with the engine.

The contraction of the passage for the gas by the nozzle f constitutes the chief 75 feature of the invention, for by such contraction the action of the engine during each suction stroke is prevented drawing over the dust from the producer, the proportions of the outlet a and that of the nozzle f being such that the suction of the engine has no appreciable effect on the bulk 80 of the gas within the producer and thus allows the dust to remain in a quiescent state, or nearly so, within the producer. 85 The accumulated dust will be removed in the ordinary course of stoking. The nozzle f may be substituted for nozzles of different degree of taper, according to requirements.

By reason of the pipe e being wider than the pipe c , the gas and water pass straight down from the nozzle and there is thus little chance of any tar adhering to the pipe e . Within the pipe i is an open spirally arranged channel k supported by a central 90 spindle l resting on a cross bar m . Into this channel flows water admitted through a pipe n . After leaving the pipe e via branch h' the gas flows upward through the pipe i and, on its way to the pipe j , comes 95 in contact with the water, and is thereby cooled and relieved of some of the tar, etc. The pipe i has openings covered by removable doors down one side to facilitate access 100 to the channel.

The extractor, shown to a larger scale in Fig. 5, consists of a circular box-like casing o having a circumferential channel o' similar to that of a centrifugal pump. Within the casing is a fan q composed of a 110

central disk q' and a series of sheet metal vanes q^2 on each side of the disk, which vanes radiate from the center to the periphery of the disk. On each side of the fan 5 and at the outer ends of the vanes is a sheet metal ring q^3 , each ring, in conjunction with the disk and vanes, forming a series of passages which come opposite the circumferential channel o' in the fan casing. Upon one 10 side of the fan is a further but smaller disk q^4 and further vanes q^5 , these latter and the disk constituting a separate fan or propeller, and being on the outlet side of the larger fan. At its lower part the fan casing is 15 divided by a vertical partition r into two passages s , s^2 , one forming the inlet and the other the outlet to the fan casing.

On the fan being set in motion, the gas 20 is first drawn through the inlet passages s' into the fan casing o , then passed into contact with the vanes o' on one side of the large fan, which fling it outward, and through the passages at the edge of the fan into the circumferential channel. On the 25 gas reaching the outer edge of the disk q it is then drawn by the smaller fan through the passages on the other side of the disk and finally delivered through the outlet passage s^2 . Any tar in the gas is received by 30 the channel o from whence it escapes into the tangential outlet passage o^2 leading to a suitable receiver. During the passage of the gas through the extractor jets of water 35 may be delivered on to the fan on both sides, the water passing along with the gas and helping to remove the tar.

The extractor will usually be fitted to a settling tank t divided into two compartments, see Fig. 1, the gas inlet being in one

and the outlet being in the other compartment. 40

What I claim is:

1. In combination, a gas producer having an outlet the sides of which are tangential to the inner face of the producer and converge in plan, a pipe for conveying the gas from the producer outlet, a junction box into which the said outlet pipe opens, a further pipe depending from the said junction box, a conical nozzle, with its narrow end 45 farthest from the said junction box within said pipe, means for delivering a constant stream of water to the inner face of the nozzle, a further pipe to which the said outlet pipe is connected near its lower end, and 50 means for delivering water in a helical path through such further pipe, and a rotary fan coupled to the said further pipe for drawing the gas through the said pipes and junction box, as set forth. 55

2. In combination, a gas producer having an outlet the sides of which are tangential to the inner face of the producer and converge in plan, a pipe for conveying the gas from the producer outlet to an engine, said 60 pipe being of larger diameter at one part than another, and a conical nozzle at the junction of the two parts, and said point of junction being in a vertical part of the pipe and the nozzle pointing downward, as set 65 forth. 70

In witness whereof I have hereunto set my hand in the presence of two witnesses.

CHAS. WHITFIELD.
